UNITED STATES PATENT OFFICE.

DAVID J. O'BRIEN, OF OMAHA, NEBRASKA.

CANDY-PACKAGE.

SPECIFICATION forming part of Letters Patent No. 777,132, dated December 13, 1904.

Application filed October 31, 1902. Renewed August 5, 1904. Serial No. 219,633. (No model.)

To all whom it may concern:

Be it known that I, DAVID J. O'BRIEN, residing at Omaha, in the county of Douglas and State of Nebraska, have invented certain useful Improvements in Candy-Packages; and I do hereby declare that the following is a full, clear, and exact description of the invention, such as will enable others skilled in the art to which it appertains to make and use the same, reference being had to the accompanying drawings, which form a part of this specification.

This invention relates to a new and useful improvement in candy-packages.

The aim of my invention is to provide a candy-package especially adapted to be sent through the mails or by express in a jacket from which the buyer may remove the candy-holding receptacle and inspect the contents before accepting same without breaking the package, the object of the invention being, further, to provide a practically air-tight package.

In the accompanying drawings I have shown in Figure 1 a top view of a package embodying my invention. Fig. 2 shows an end view thereof, while Fig. 3 shows a central sectional view of a candy-package on line xx' of Fig. 1.

The package trade, relating especially to confections, has grown to considerable proportions; but it is found that the buyers of candy occasionally object to buying goods in a closed package the contents of which they cannot inspect. The candy-dealer would not permit the packages being broken or opened, as that would spoil the market value of the package should the party inspecting the package refuse to buy after inspection.

In order to provide a practically air-tight package which will prevent the goods from granulating and in which the candy may be shipped and readily inspected without breaking the package is the aim and object of my invention.

In my invention I construct an outer open-ended pocket or shipping-jacket A, made preferably of strawboard or so-called "pasteboard," which is collapsible, so that this shipping jacket or pocket can be flattened out or folded. This is desirable in that when the goods are exposed in the show-case the ship-

ping-jacket may be nicely folded below the same. In connection with my shipping pocket or jacket, which is merely a piece of "cardboard," so-called, bent to form a four-sided open-ended receptacle, the end a as shown in Fig. 3, being pasted against the remaining end, I use a suitable candy-package. This candy-package comprises a box and embodies the outer bottom 1, as shown in Fig. 3, which is provided with an oval opening, as is shown at a' in Fig. 1. From this bottom 1 extend the side and end rims 5, as is shown in Figs. 2 and 3, these side and end rims having their bottom portions bent at right angles, as is shown at b in the figure, by means of which bent portion the side and end rims are secured to the outer bottom member 1. These bottom portions b in no way interfere with the opening a' , through which the goods may be inspected. Secured to the bottom of the box and resting upon the inwardly-bent rim portions b is a suitable transparency or transparent member 2, composed of celluloid or other suitable material, as is shown in Fig. 3. Secured above this transparent member 2 is an inner bottom 3, which is also provided with a circular perforated opening a' , so that the bottom of my box comprises the members 1, 2, and 3. The side and end rims 5, it will be noticed, extend but a short distance upward. Now secured to the side and end rims 5 and preferably twice the width of the rim 5 is an inner member 9, which really forms the inner sides and ends of the box, as is clearly shown in Fig. 3, and said member 9 provides means for maintaining the top and bottom sections in their relative positions when the package is closed.

The top of my candy-package comprises the outer top 6, which is provided with an oval opening a' , as is shown in Fig. 1, and below which is secured the angular portion c of the upper rim 8, which forms the lid-flange of the box just as the rim members 5 form the bottom flange of the box. This lid-rim 8 is also provided with the oval opening a' , as is shown in Fig. 3, and below the same is secured the transparent member 2, which is suitably secured to the lid and upon which rests and

is secured the inner top member 4 to secure the interposed transparent member 2 of celluloid or other transparent material.

It will be noticed that the combined width 5 of the two rim members 8 and 5 are of a width equal to the width of the inner sides and ends 9, so that when the box or candy-package is closed the sides and ends are protected by two thicknesses of material, while the top and 10 bottom are provided with the transparent members 2. It will further be noticed that the outer bottom 1 and the outer top 6 project a suitable distance beyond the sides and ends, so as to provide a box having a shoulder 15 or flange, as shown.

Now in the use of this box the candy or other confectionery is packed in this box and then the lid is secured. Now in order to make an air-tight package the top and bottom rims 20 after the box has been closed are secured by means of a sealing-strip 10, preferably of paper, which is pasted to the bottom and top rims and entirely surrounds the package, so that the box cannot be opened without breaking 25 the same or severing the sealing-strip 10, so that the lid may readily be removed. The contents of the box, however, may be seen through the transparent top and bottoms 2. This package is then placed within the open- 30 ended pocket or shipping-jacket A and tied, so that the same cannot slide out of the same.

In packages which are constructed according to my invention the goods may be readily inspected, and in making the package air-tight the goods will be preserved.

It will be noticed that the transparent members 2 are forced against the top and bottom by means of the inner side and end members 9, so that a package is provided which will 40 stand considerable agitation in shipping the same.

These candy-packages are made of any suitable size and material.

Having thus described my said invention, 45 what I claim as new, and desire to secure by United States Letters Patent, is

1. A package of the class described, comprising complemental sections each of which is formed of an outer member having an opening 50 therein for exposing to view the contents of the package, a rim member provided with an inwardly-extending horizontally-disposed flange which latter is secured to the outer member around the opening thereof, a trans- 55 parent member arranged within the rim member and seated upon said flange, said transparent member extending over the opening of the outer member to close said opening, and a side and end member arranged within 60 the sections and providing means for maintaining the sections in their relative positions when the package is closed.

2. A package of the class described, comprising complemental sections each of which is

formed of an outer member having an opening 65 therein for exposing to view the contents of the package, a rim member provided with an inwardly-extending horizontally-disposed flange which latter is secured to the outer member around the opening thereof, a transparent member arranged within the rim member seated upon said flange, said transparent member extending over the opening of the outer member to close said opening, an inner member seated upon the transparent member, and a side and end member arranged within the sections and of a width approximately equal to the space between the inner members of the sections, said side and end member providing means for maintaining said sections in their relative positions when the package is closed.

3. A package of the class described, comprising complemental sections each of which is formed of an outer member having an opening 85 therein for exposing to view the contents of the package, a rim member provided with a flange which latter is secured to the outer member, a transparent member arranged within the rim member and extending over the opening of the outer member to close said opening, and a side and end member arranged within the sections and providing means for maintaining the sections in their relative positions when the package is closed, the outer 95 members of the sections projecting beyond the sides and ends of the package to form overhanging flanges, in combination with an open-ended pocket in which the packages may be secured for shipping.

4. A package of the class described, comprising complemental sections each of which is formed of an outer member having an opening 105 therein for exposing to view the contents of the package, a rim member provided with a flange which latter is secured to the outer member, a transparent member arranged within the rim member and extending over the opening of the outer member to close said opening, a side and end member arranged 110 within the sections and providing means for maintaining the sections in their relative positions when the package is closed, and a sealing-strip arranged upon the exterior of the rim members for securing the sections of the 115 package together.

5. A package of the class described, comprising bottom and top sections, the top section being formed of an outer member having an opening 120 therein for exposing to view the contents of the package, a rim member provided with an inwardly-extending horizontally-disposed flange which latter is secured to the outer member around the opening thereof, said rim member being designed to engage 125 the bottom section for holding the top section thereon, and a transparent member arranged within the rim member and seated upon said

flange, said transparent member extending over the opening of the outer member to close said opening.

6. A package of the class described, comprising bottom and top sections, the top section being formed of an outer member having an opening therein for exposing to view the contents of the package, a rim member provided with an inwardly-extending horizontally-disposed flange which latter is secured to the outer member around the opening thereof, said rim member being designed to engage the bottom section for holding the top section

thereon, a transparent member arranged with in the rim member and extending over the opening of the outer member to close said opening, said transparent member being seated upon the flange of the rim member, and an inner member seated upon the transparent member and having an opening therein. 15 20

In testimony whereof I affix my signature in presence of two witnesses.
